Attorney.

UNITED STATES PATENT OFFICE.

THEODOR ZANGER, OF ERIE, PENNSYLVANIA, ASSIGNOR TO JACOB W. SEIP,
OF SAME PLACE.

MAGNETIC PENDULUM-LEVEL.

SPECIFICATION forming part of Letters Patent No. 546,501, dated September 17, 1895.

Application filed October 28, 1893. Renewed June 6, 1895. Serial No. 551,790. (No model.)

To all whom it may concern:

Be it known that I, THEODOR ZANGER, a citizen of the United States, residing at Erie, in the county of Erie and State of Pennsylvania, have invented certain new and useful Improvements in Magnetic Pendulum-Levels; and I do declare the following to be a full, clear, and exact description of the invention, such as will enable others skilled in the art to 5
10 which it appertains to make and use the same, reference being had to the accompanying drawings, and to the letters of reference marked thereon, which form a part of this specification.

15 My invention relates to improvements in magnetic pendulum-levels; and the object of the invention is to produce a pendulum-level that is always reliable and will denote the exact degrees on an accurately-divided dial and 20 in such manner that the vibrations or trembling of the pointer usually occurring with the ordinary pendulum-levels is entirely obviated or prevented; also, to accomplish this by very simple devices that are not liable to 25 get out of order, but will always accurately designate the level-line; furthermore, to attach the weighted pendulum and the pointer on a pin or shaft, having at each end a needle-point, which points are journaled in corresponding journals drilled into the glass front and back so as not only to make the pointer very sensitive, but also to form a very hard and durable bearing-surface, and, finally, to 30 produce this magnetic pendulum-level at a very reasonable expense.

35 My invention consists in the construction of certain peculiar details and arrangement of parts, as will be more fully described hereinafter, and specifically pointed out in the 40 claims, reference being had to the accompanying drawings and the letters marked thereon.

Like letters indicate similar parts in both figures of the drawings, in which—

Figure 1 represents a sectional elevation of 45 my improved magnetic pendulum-level. Fig. 2 is a horizontal section on the line 2 2 of Fig. 1.

In the drawings, A represents the body or stock of the level, preferably made of metal, although it may be made of wood or any other suitable material, and it may be plain or ornamental, as desired. This stock is provided with a short cylinder or casing B, having at each end a screw-thread to receive the heads C and D, provided with flanges to receive 50 glass plates or disks E and F, and forming the front and back of the cylinder of the level. If desired, the heads C and D may be made plain—i. e., the screw-threads may be dispensed with and two or more screws, bolts, or rivets may be employed to secure said cylinder and heads together. The inside of the cylinder B is provided with an annular rib or projection b, to which two pieces of thin magnetized steel c forming liners are secured. A weighted 55 pendulum G, having a convex face, is also provided with a piece of similar thin magnetized steel g forming its face, and it is arranged as close as possible to the projection b and its liner, so as to be attracted by it. This pendulum is secured to a pin or short shaft h, having a needle-point at each end, and said needle-points are journaled in small depressions of similar shape to receive said needle-points. The depressions are drilled or ground 60 into the glass plates E and F, thus forming very accurate and hard bearings for the needle-points. To the shaft h the pointer or index H is secured, being, as shown, double pointed, and if paper or equivalent dials are 65 used it must be placed in front of them. It will be readily understood that by magnetizing the steel liners the action of the pendulum and pointer will be very steady and all vibrations will be entirely obviated, and levels of any kind can be accurately ascertained 70 and noted.

Having thus described my invention, what I claim is—

1. In a magnetic pendulum level the combination of a cylinder having a magnetic liner, and the glass front and back, with a shaft provided with needle-points journaled in said glass front and back, and a pendulum with 75 80 85 90

magnetized face and a pointer secured to said shaft, all arranged as specified.

2. The magnetic pendulum level herein described, consisting of the stock A having the cylinder B provided with magnetic inner surface, attached to it, and having a glass front and back, in which the needle-pointed shaft *h* is journaled, and carrying the pendulum G

having magnetized face and the pointer II, all constructed and operating as specified. 10

In testimony whereof I affix my signature in presence of two witnesses.

THEODOR ZANGER.
